UNITED STATES PATENT OFFICE.

ARTHUR BURGESS, OF PHILADELPHIA, PENNSYLVANIA, ASSIGNOR TO
JOSEPH H. BROMLEY, OF PHILADELPHIA, PENNSYLVANIA.

DESIGN FOR A LACE CURTAIN.

SPECIFICATION forming part of Design No. 35,921, dated May 20, 1902.

Application filed April 14, 1902. Serial No. 102,939. Term of patent 7 years.

To all whom it may concern:

Be it known that I, ARTHUR BURGESS, a subject of the King of Great Britain, residing at Philadelphia, in the State of Pennsylvania, have invented and produced a certain new and original Design for a Lace Curtain, of which the following is a full, clear, and exact description, reference being had to the accompanying drawing, forming a part of this specification.

My invention relates to the surface ornamentation of woven fabrics in which the ornamental pattern or design is produced in the weaving; and it consists in a woven design for a lace curtain, as illustrated in the accompanying drawing, in which is represented the broken-off lower end of one of a pair of like curtains.

Within an edge border (indicated by the parallel border-lines *a a*) is the novel design invented and produced by me for the body of the curtain. Its leading and characteristic feature is a series of scrolls superposed upon

a series of rectangular figures. The latter is in the form of a walls-of-Troy figure *b*, and the superposed figure is a series of scrolls *c*, facing inwardly and outwardly alternately. These scroll-figures meet each other except at the corner of the curtain-body design, where an ornamental corner figure *d* forms the connection. A small vine-like figure *e* is added to fill up otherwise blank spaces and make a complete and concrete pattern.

Having thus described my invention, what I claim as new, and desire to secure by Letters Patent, is—

The design for a lace curtain, substantially as shown and described.

In testimony whereof I have hereunto affixed my signature this 12th day of April, A. D. 1902.

ARTHUR BURGESS.
